No. 36,327.

Patented May 12, 1903.

UNITED STATES PATENT OFFICE.

GEORGE H. ULLMAN, OF NEW YORK, N. Y.

DESIGN FOR A CHANDELIER.

SPECIFICATION forming part of Design No. 36,327, dated May 12, 1903.

Application filed January 6, 1903. Serial No. 138,075. Term of patent 8½ years.

To all whom it may concern:

Be it known that I, GEORGE H. ULLMAN, a citizen of the United States, residing in the borough of Manhattan, city of New York, State of New York, have invented and produced a new, original, and ornamental Design for Chandeliers, of which the following is a description.

My new design is illustrated in the accompanying drawing, forming part hereof; and it consists of the globular body 1, surmounted by the vase-like extension 2, the bowl and lip of which carry ovoid ornamentation, the ring 3, the stem 4, carrying a band, the vase-like canopy or bell 5, the bowl and lip of which carry ovoid ornamentation, the horizontal arms 6, extending out from the body 1 and each having an overlapped rear portion 7

and an upwardly - rising forward portion 8, provided with the globe-holding canopies 9, from which depend spherical globes, that portion of the globular body 1 between the bases of the portions 7 of the arms being ornamented with rectangular paneling.

Having now described my invention, what I claim as new, and desire to secure by Letters Patent, is—

The ornamental design for a chandelier herein shown and described.

This specification signed and witnessed this 3d day of January, 1903.

GEORGE H. ULLMAN.
